United States Patent Office

Des. 219,101
Patented Nov. 3, 1970

219,101

POWERED INVALID CART

Bert J. Goletski, Culver City, Calif., assignor to Everest
& Jennings, Inc., Los Angeles, Calif., a corporation
of California

Filed Jan. 17, 1969, Ser. No. 15,386

Term of patent 7 years

Int. Cl. D6—01

U.S. Cl. D15—1

FIG. 1.

FIG. 2.

FIG. 3.

FIG. 4.

FIG. 5.

FIG. 6.

FIG. 1 is a perspective view of a powered invalid cart embodying my new design;

FIG. 2 is a side elevational view of the same;

FIG. 3 is a front elevational view of the same;

FIG. 4 is a top plan view of the same;

FIG. 5 is a rear elevational view of the same;

FIG. 6 is a perspective view of the same with the side panels in lowered position.

I claim:

The ornamental design for a powered invalid cart, as shown and described.
